UNITED STATES PATENT OFFICE.

AMELIA SILCOX, OF ARENZVILLE, ILLINOIS.

DESIGN FOR A CURTAIN.

No. 37,598.

Specification for Design.

Patented Oct. 24, 1905.

Application filed July 28, 1905. Serial No. 271,702. Term of patent 7 years.

To all whom it may concern:

Be it known that I, AMELIA SILCOX, a citizen of the United States, residing at Arenzville, in the county of Cass and State of Illinois, have invented a new, original, and ornamental Design for Curtains, of which the following is a specification, reference being had to the accompanying drawing, forming a part thereof.

In the drawing accompanying the specification and made a part thereof the figure is a side elevation of a part of a curtain, showing my design.

I claim—

The ornamental design for a curtain as shown.

AMELIA SILCOX.
